UNITED STATES PATENT OFFICE

SWAN M. LINDSTRAND, OF CHICAGO, ILLINOIS

FLOATING AIR LINER

Application filed April 9, 1928. Serial No. 268,433.

This invention relates to improvements in a floating air liner, and has for one of its principal objects, the provision of means for facilitating the handling of a large type airplane, when in flight, such as would be used for trans-Atlantic or trans-continental air travel.

One of the important objects of this invention is to provide a plural means for controlling the elevation and depression of the plane, the said means comprising a pair of independently operated elevators positioned at the forward and rearward ends of the plane.

Another important object of this invention is the provision of an elevator control mechanism which eliminates to a great extent the transmission of shocks and the like from the elevators to the operator's control, more particularly, a system of indirectly operated elevators. With this means of indirectly controlling the elevators, in normal flying, the tenseness of the operator's grip upon the elevator control is greatly relieved. Smoother riding necessarily results from this stabilized means of control, which is a very important consideration in passenger and freight air transportation.

A further important object of this invention, is the provision of a buoyant fuselage construction which permits a safe landing to be made on water. It is to be understood, this is not a hydro-airplane, but the feature of floating is merely an added safety measure in case a forced landing is to be made on water.

Another and further important object of the invention is to provide a plurality of sectional fuel tanks which will prevent an abnormal shifting of the weight of the liquid fuel when the plane is in a position other than horizontal.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of the airplane of this invention, illustrating the positioning of the elevators upon the fuselage.

Figure 2 is a top plan view of the device shown in Figure 1, portions of the main wing being broken away.

Figure 3 is a front view of the airplane.

Figure 4 is a partial sectional elevation, showing the separate control means for the front and rear elevators.

Figure 5 is an end sectional view of the control cockpit.

Figure 6 is a top view of the elevator control mechanism.

Figure 7 is a detail sectional view of one of the elevator operating drums.

As shown in the drawings:

The reference numeral 10 indicates generally the fuselage of an improved air liner, the front end of which is supported by a forward landing gear and accompanying wheels 12, the empennage or rear end of the fuselage being also supported by a rear landing gear 14. The fuselage 10 is constructed water-tight and provides a floating means in case the machine is forced down while flying over water. The forward end of the fuselage terminates in a bullet-shaped nose, thereby decreasing air resistance in flight. Mounted on the rear extremity of the body 10 is a rudder 16 of the ordinary construction.

Positioned upon the upper portion of the fuselage is a flying wing 18 of the established aerofoil construction, and a cabin 20 for the accommodation of a plurality of passengers and the pilot, is located immediately beneath the wing and forms part of the fuselage. Mounted in front of the wing 18, and with one positioned on each side of the fuselage 10 is a pair of tractor motors 22 and their accompanying propellers 24. Directly behind the motors 22 and at the rear of the wing 18 are two pusher motors 26 and their companion propellers 28. The motors 22 and 26 are mounted between braces 30 and 32 and extensions 34.

It is apparent that a plane equipped with this number of motors would be capable of carrying a great amount of weight, hence a

large number of passengers could be accommodated and inasmuch as an abundant supply of fuel could be also carried, the plane's 5 cruising range would be very extensive. A fuel tank 36 is suspended from each member 34 by means of brackets 38, and is divided internally into a number of sections as shown in Figure 1 in dotted lines at 40. A pipe line leads from each section and by suitable valve 10 means, fuel may be drawn from any desired section. If all the fuel was contained in one large tank, when climbing or descending the shifting of the fuel in the tank might cause an undesirable concentration of weight at either 15 end of the tank, thereby tending to unstabilize the ship. But with the sectional tank when the plane is in a position other than horizontal the troublesome shifting of the fuel weight is eliminated.

20 Pivotaly mounted upon the forward and rearward portions of the fuselage, is a set of elevators 42 and 44 respectively. Each set comprises a pair of planes, one mounted on each side of the fuselage, the elevators 42 being hinged at their forward edge to the element 46 and the rear elevators 44 are similarly hinged at their rearward edge to the element 48.

30 Rigidly attached at right-angles to the side end of the rear of the forward elevators 42 and wrapped around a portion of the surface of the same and adjacent the fuselage is an element 46, the rear portion of the said element being shaped in an arc of a circle as 35 shown at 48. Two ends of a cable 50 are attached to the member 48, one end attached at each extremity of the arc.

40 Positioned adjacent the member 48 and adapted to make rolling contact with the curved surface thereof is a drum 52. Both ends of the cable 50 are attached to the said drum, and the cable is wrapped several times around the drum and then around the convex surface of the element 48, so that when the 45 drum is rotated the cable winds on one side of the drum and unwinds on the other side.

Hence the element 48 is moved substantially vertically either up or down as the case may be, thus lowering or raising the ends of the 50 elevators on both sides of the fuselage, the two drums co-acting through the medium of a connecting shaft 54.

A similar construction exists with respect to the rear elevators 44 with the difference that 55 an element 56, corresponding to the element 48, is mounted on the forward portion of the elevator 44, and co-acts with a drum 58.

Means for rotating the drums 52 and 58, 60 comprise two independently operated shafts 60 and 62 respectively. Mounted on the shaft 60 is a worm wheel 64 which in turn operates a gear 66 mounted rigidly on the shaft 54. Mounted on the shaft 62 is another worm wheel 68 which operates a gear 70 rigidly 65 positioned on a shaft 72. Wrapped upon the

shaft 72 and a rear drum shaft 74 is a pair of connecting cables 76. It is upon this rear shaft 74 that the drums 58 are mounted.

70 Mounted on the inner end of the shaft 60 is a pinion gear 78 and also mounted upon the inner end of the shaft 62 is a like pinion 80. The pinion 80 is operated by a gear 82 which is mounted on one end of a hollow shaft 84, upon the other end of which is an operator's handwheel 86. The pinion 78 is operated by 75 a gear 88 mounted on one end of a shaft 90 which is rotatably positioned inside the shaft 84, and upon the other end of which is a handwheel 92. Both wheels turn independently and through the respectively associated mechanisms of each, the elevators 42 and 44 are 80 independently moved up and down, as required.

It is apparent that herein is provided an aircraft whose general proportions, means of 85 control, safety features ideally adapted it for commercial passenger travel. The elevator control being such as to eliminate the nerve-racking task of piloting a plane for long periods at a time and providing features of 90 safety, ease of operation and stability, requisite to successful air-line travel.

I am aware that many changes may be made and numerous details of construction 95 varied throughout a wide range without departing from the principles of this invention, and I therefore do not purpose limiting the patent granted hereon otherwise than as necessitated by the prior art.

I claim as my invention:

100 A floating air-liner, including in combination, a fuselage and a pair of elevating planes mounted on the front and rear of the fuselage, respectively, and means for separately operating each pair of elevating planes, said means comprising a rotatable drum, a cable wrapped around the drum, the ends of the cable connected to the elevator, and means for supporting the cable ends, said means including an arcuate member at one inner corner of 105 the elevator, a system of gears associated with each pair of elevators, and manually controlled means for operating each system of gears, said manually controlled means comprising two independently rotated hand-wheels mounted on the same shaft.

110 In testimony whereof I affix my signature.

115 SWAN M. LINDSTRAND.
